COMBINED SAFETY FLASHER SWITCH AND INDICATOR LIGHT FOR THE CONVERSION OF THE FRONT AND REAR AUTO LIGHTS INTO SAFETY SIGNAL FLASHERS

Robert D. Kahn, Rockville Centre, N.Y., assignor to Fedtro, Inc., Rockville Centre, N.Y., a corporation of New York

Filed May 24, 1967, Ser. No. 7,253

Term of patent 14 years

(Cl. D26—13)

FIG. 1

FIG. 2

FIG. 5

FIG. 3

FIG. 6

FIG. 4

FIG. 7

FIG. 1 is a front elevational view of my new design for a combined safety flasher switch and indicator light for the conversion of the front and rear auto lights into safety signal flashers;

FIG. 2 is a rear elevational view of my new design;

FIG. 3 is a top plan view of my new design;

FIG. 4 is a bottom plan view of my new design;

FIG. 5 is a right side elevational view of my new design, the left side view being similar;

FIG. 6 is a cross sectional view taken substantially along the line 6—6 of FIG. 1; and

FIG. 7 is a cross sectional view taken substantially along the line 7—7 of FIG. 1.

I claim:

The ornamental design for a combined safety flasher switch and indicator light for the conversion of the front and rear auto lights into safety signal flashers, substantially as shown and described.
